(57) **CLAIM**

The ornamental design for a handle for pastry blender, as shown and described.

DESCRIPTION

FIG. 1 is a perspective view of a pastry blender handle according to the present invention;

FIG. 2 is a front elevational view of the pastry blender handle shown in FIG. 1;

FIG. 3 is a rear view of the pastry blender handle shown in FIGS. 1 and 2;

FIG. 4 is a top view of the pastry blender handle shown in FIGS. 1-3;

FIG. 5 is a bottom view of the pastry blender handle shown in FIGS. 1-4;

FIG. 6 is an enlarged left side view of the pastry blender handle shown in FIGS. 1-5;

FIG. 7 is an enlarged right side view of the pastry blender handle shown in FIGS. 1-6; and,

FIG. 8 is a perspective view of the pastry blender handle, the broken line showing of a pastry blender is for illustrative purposes only and forms no part of the claimed design.
